PHONOGRAPH APPARATUS

Paul H. Smyth, Jr., Chicago, Ill.

Application March 14, 1935, Serial No. 11,092

9 Claims. (Cl. 274—10)

This invention relates to a phonograph apparatus.

It is an object of this invention to provide an improved phonograph apparatus which is relatively simple and inexpensive in construction and efficient in use.

Another object of the present invention is to provide a new and improved record-selecting device for an automatic phonograph.

10 A further object of the present invention is to provide a new and improved record-selecting device for an automatic phonograph and a new and improved device for manually and simultaneously resetting all of the record-selecting bars back 15 into their initial or reset positions.

Other objects will appear hereinafter.

The invention consists in the novel combination and arrangement of parts to be hereinafter described and claimed.

20 The invention will be best understood by reference to the accompanying drawing, showing the preferred form of construction and in which:

Fig. 1 is a front elevational view of the new selector device;

25 Fig. 2 is a vertical sectional view of the same on line 2—2 in Fig. 1;

Fig. 3 is a sectional view on line 3—3 in Fig. 1;

Fig. 4 is a sectional view on line 4—4 in Fig. 1;

Fig. 5 is a sectional view on line 5—5 in Fig. 1.

30 The present application relates particularly to an automatic phonograph apparatus and selector mechanism therefor.

A preferred form of the new selector device is shown in the drawing, is therein generally indicated at 10, and comprises a supporting frame 11 which is adapted to be arranged in a phonograph cabinet, a horizontal partition or wall 12 of such a cabinet being shown; the front wall of such a cabinet being indicated at 13 (Fig. 2).

40 Adapted to be arranged in the front wall 13 of a phonograph cabinet is a plate 14 which is formed as part of the supporting frame 11, and slidably mounted in this panel 14 are two vertical rows of push buttons 15.

45 Arranged inwardly of the plate 14 is a vertically extending bank of selector bars 16, each of which has one end portion pivotally mounted, as at 17, in a vertical side wall 18 of the frame 11 (Fig. 4).

50 At its opposite end, that is, at the end of the same opposite the end which is pivotally mounted at 17, each of the selector bars 16 has a notched portion 19 and projecting into each of these notched portions 19 is a bar 20. These bars 55 20 are pivotally mounted, as at 49, in slots which

are formed in a vertical wall 22 of the cabinet, and arranged on each of the bars 20 is a spring 21.

The present record-selecting device comprises a swinging carriage 23 which includes a vertical guide member 24 and a slide bar 25 which is slidably mounted upon the guide member 24 for movement relative thereto; and provided on this slide bar 25 is a lateral extension or lug 26.

Pivotedly mounted, as at 28, on the supporting frame 11 is a resetting member 27 which includes a vertically extending portion 29, this resetting member 27—29 having an arm 30 which is arranged in the path of the inner end portions 32 of a resetting plunger 33 (Fig. 5).

The resetting plunger 33 is slidable in the bore 33 of a push button 31 and arranged on the plunger 33, within an enlarged portion 34 of the bore 33, is a resetting spring 35.

The resetting member 27—29 also includes a vertical bar portion 36, and this bar portion 36 is engageable with the end portions 37 of the selector bars 16.

Pivotedly mounted upon the supporting frame 11, as at 38, is an automatic selector 39 and this selector 39 has a vertically extending portion 40 which is projectible into a series of registered or aligned notches 41, one of these notches 41 being formed in each of the selector bars 16. This automatic selector device 39 is described and claimed in the applicant's copending application, Ser. No. 22,701, filed May 22, 1935 for Phonographs, and only so much of it is herein shown and described in this application as is necessary for an understanding of the subject matter 35 claimed in the present application.

Each of the push buttons 15 is provided with a bore or slot 48 and slidably mounted in each of these bores 48 is a plunger 42; a resetting spring 43 being arranged on each plunger 42 within an enlargement of the corresponding bore 48.

Operation

In order to make a selection of one or more records which he desires to play, the operator 45 of the phonograph apparatus embodying the present invention pushes inwardly upon a corresponding number of the selector buttons 15, thereby pushing the plungers 42, which are associated with the selected buttons, inwardly against the action of their resetting springs 43. This movement of the selector buttons 15 and their plungers 42 pivots the corresponding selector bars 50 16 (from full to dotted line position, Fig. 4), and 55

during this movement of the bars 16, the members 20 are moved or snapped past dead center position, in the notched end portions 19 of the selector bars 16, against the action of their resetting springs 21, thereby retaining the selector bars 16 in dotted line position (Fig. 4).

At a certain time during the automatic operation of the selector carriage 23, the slide bar 25 drops or slides down on its guide 24 until the lateral extension or lug 26 on the slide bar 25 engages, and comes to rest upon, the upper surface of the uppermost selector bar 16 which has been pressed inwardly or moved into effective position (as is illustrated in Fig. 2). This engagement of the lug 26 of the automatic selector carriage 23 upon the upper surface of the uppermost actuated selector bar 16 plays an important part in completing the record-selecting operation (which is described in my copending application), and after the record-selecting and playing operations have been completed, the actuated selector bars 16 may be reset manually into their initial positions by actuating the resetting push button 31.

In order to reset the selector bars 16 manually into their initial positions, the push button 31 may be pushed inwardly (left to right, Fig. 2, bottom to top, Fig. 5) thereby moving its plunger 33, against the action of its resetting spring 35, into engagement with the extension 30 of the resetting member 21, thereby pivoting the resetting member 27, at 28, against the action of its resetting spring 44, from full to dotted line position (counterclockwise, Fig. 5). This movement of the resetting member 27 causes the vertically extending portion or bar 38 thereof to engage the aligned end portions 37 of the selector bars 16, whereupon the selector bars 16 are moved (from dotted to full line position, Fig. 4). During this movement of the selectors 16 back into their initial position, as in full lines, Fig. 4, the retaining members 20 are moved, or snapped, past dead center position, in the notched portions 19 of the bars 16, thereby retaining the selector bars 16 in their initial or reset position, wherein they are stopped and held by engagement of the notched portions 41 of the bars 16 with the vertical bar portion 40 of the member 39; this member 39 having only a limited movement (clockwise, Fig. 3) by reason of having an arm 45 which engages against a wall 46 of the frame 11, (Fig. 3), when the bars 16 are moved back into their initial positions and engage the bar portion 40 of the member 39.

While I have illustrated and described the preferred form of construction for carrying my invention into effect, this is capable of variation and modification, without departing from the spirit of the invention. I, therefore, do not wish to be limited to the precise details of construction set forth, but desire to avail myself of such variations and modifications as come within the scope of the appended claims.

Having thus described my invention what I claim as new and desire to protect by Letters Patent is:

1. A selector mechanism for automatic phonographs, said mechanism including a support, a plurality of selector members mounted on said support for back and forth movement into and out of selecting position, reciprocably movable members carried by said support for moving each of said arms toward selecting position, spring-urged toggle mechanism for each of said selector members and cooperable therewith to move

and yieldably hold the same in selecting or non-selecting position upon movement of a said selector member toward either of said positions, reset means including a member movable on said support to engage and move said arms from selected toward non-selected position, means including a reciprocably movable member for operating said reset member, and means including a member movably carried on said support for engagement with all of said selector members to move the same jointly into selecting position.

2. Selector mechanism for automatic phonographs, said mechanism including a support, a plurality of pivoted selector members on said support and pivotable into and out of selecting position, push-button members carried by said support for moving each of said selector members toward selecting position, and spring-urged toggle means operatively engaging the end portion of each of said selector members and cooperable with the latter to move the same into selecting position when said selector member has been moved a predetermined distance by a corresponding push-button member.

3. A selector mechanism for automatic phonographs including a support, a plurality of pivoted selector arms on said support and pivotable into and out of selecting position, manual selecting members on said support for moving each of said selector arms toward selecting position, snap-action mechanism arranged at the end of each said arm for operative engagement therewith and constructed to move a said arm positively into selecting position when said arm has been moved a predetermined distance by a corresponding push-button member.

4. A record selector mechanism for phonographs and including a support having pivoted thereon a plurality of selector members movable into and out of selecting position, selector buttons operable to move said selector members severally toward selecting position, a reset member and a bail movable thereby to engage and return one or all of said selector members from selecting to non-selecting position, together with spring-biased mechanism cooperable with each of said selector members and constructed to move said selector members severally into selecting or non-selecting position after the same have been moved a predetermined distance toward one or the other of said positions either by said selector buttons or by said reset member, respectively.

5. Selecting mechanism including a plurality of selector bars each movable back and forth into and out of selecting position, a plurality of selecting plungers each operable to move one of said bars toward selecting position and including a master plunger and a bail movable thereby to engage and move all of said bars toward selecting position and also a reset plunger and a bail movable thereby to engage one or more of said bars in selecting position and move said bar or bars out of selecting position, together with means cooperable with each of said bars and automatically operable to move a said bar positively into or out of selecting position when said bar has been moved a predetermined distance toward either of said positions.

6. A record selecting device for automatic phonographs comprising: a frame member having a plurality of arms pivoted therein for movement into and out of selected position; said arms having a notched end portion; a plurality of slideable selector members each slideable to engage one of said arms and move the latter into selected position; and a plurality of toggle members

- mounted on said frame and each having an end portion engageable with the said notched portion in the end of one of said arms.
7. A record selecting device for automatic phonographs comprising: a frame; a plurality of selector arms mounted in said frame for pivotal movement into and out of selected position; a plurality of selector buttons each engageable with a said arm to move the latter into selected position; pivoted means on said frame engageable with an end portion of each said arm and operable to move the latter past its dead-center position relative to said pivoted means when said arm is moved into and out of selected position; and means limiting the pivotal movement of said arms in both directions from dead-center position relative to the pivoting of said arms.
8. A record selecting mechanism for phonographs comprising a frame member; a plurality of selector arms mounted for pivotal movement thereon into and out of selected position; selector plungers each slidably to move a said arm into selected position; means on said frame having operative engagement with each of said arms to automatically urge the latter into and out of selected position when said arm is moved a predetermined distance toward either said position; a reset arm pivoted in said frame for engagement with said arms to move the latter from selected to non-selected position; and a slidable member operable to pivot said reset member into reset engagement with said arms.
9. A selector mechanism for automatic phonographs comprising a frame; a plurality of selector arms pivotally mounted therein for movement into and out of selected position; slidable members for moving each of said arms into a selected position; pivoted means on said frame engaging each of said arms in toggle relationship and operable to move said arms off of dead-center position relative to their several pivotal axes when said arms are pivoted a determined distance; a reset member movable in said frame to move said arms from selected to non-selected position; means for operably moving said reset member and a member movable in said frame and operable to move all of said arms in selected position.
